UNITED STATES PATENT OFFICE.

OTTO E. HEISSE, OF CHICAGO, ILLINOIS.

PORTABLE HEATING CABINET.

Application filed December 8, 1926. Serial No. 153,248.

This invention relates generally to portable heating cabinets and is more especially pertinent to a portable cabinet which is adapted to house a fuel oil burner and its necessary accessories.

In heating large rooms such as halls for public gatherings where no permanent heating system is installed, it is desirable to have a heater capable of producing a large amount of heat, and at the same time adapted to be readily and easily moved from place to place. Great difficulty has been encountered heretofore in providing a heater which, if capable of giving a sufficient amount of heat, could be moved with any great facility. It is an object of this invention to provide a heater embodying a fuel oil burner capable of generating a large amount of heat, and installed in a suitable cabinet which is adapted to be moved from place to place.

It is a more specific object of this invention to provide a portable cabinet having a compartment within which a liquid fuel oil burner operates and having a second compartment arranged to hold a fuel oil supply tank.

Other objects and advantages will become apparent from the following description and in the accompanying drawings, in which:

Figure 1 is a perspective view of the preferred form of this invention.

Fig. 2 is a longitudinal section on a line 2-2 of Fig. 3 showing the interior arrangement of the operating parts.

Fig. 3 is a top plan view.

In the preferred embodiment, as shown in the drawings, the cabinet may be substantially formed throughout of sheet metal and comprises an upright case having a front 5 and three walls 6, 7 and 8 secured together in any suitable manner. The top 9 is preferably separated from the walls and the front by an offset portion 10 which provides both an ornamental appearance and a more complete diffusion of heat as will be hereinafter described. The bottom 11 which is preferably substantially heavier in construction than the rest of the cabinet is suitably secured, as by bolts, rivets or the like, within the three walls and the front near the lower part of the case. Between the bottom and the lower edges of the sides and front is positioned a frame 12 in which a plurality of movable supporting means such as the casters 13 are mounted in the customary manner. Near the bottom of the case on the three sides thereof is

a plurality of air inlet openings 14. Similarly the top 9 and the offset portion of the top 10 are provided with air outlet openings 15.

The front of the stove in this instance has no air passages but is provided with a suitable upper door 16 and a lower door 17 through which access into the interior of the cabinet is attained. A partition 18 having therein a plurality of air passages 19 adjacent the periphery thereof is secured horizontally within the cabinet intermediate the ends in such manner that the upper door 16 opens into the upper compartment formed thereby and the lower door 17 opens into the lower compartment.

As in this type of heater a burner system capable of generating a large amount of heat is necessary, I have shown herein somewhat diagrammatically a commercial type of liquid fuel oil burner. The type of burner which is most capable of successful operation in my heater comprises a burner which, in operation, receives liquid fuel from a supply reservoir and by preheating the fuel converts it into an inflammable gas which is fed to a plurality of burner tips where combustion occurs. As shown in Fig. 2, the gas generating and burning assembly, designated generally as 20, is suitably supported within the upper compartment as by means of the brackets 21 secured to the partition 19. A pressure supply tank 22 equipped with a suitable pump 23 is contained in the lower compartment. The pressure supplied by the pump 23 to the supply tank 22 forces the liquid fuel through a connecting pipe 24 to the burner where the fuel is converted into gas and burned. Thus the cabinet provides a burner compartment which carries a suitable generator and burner and a supply compartment arranged to hold the accessories incidental to the burner.

In order to diffuse the flame from the burner and to insure a positive heating of the air passing through the cabinet, I have provided a suitable means in the form of a baffle plate positioned immediately above the burner. The baffle plate in the most desirable form comprises a flat plate 25 having downwardly turned edges 26, said plate being supported immediately above the burner by a plurality of legs 27. In this position the flame from the burner will impinge on the plate and will then be spread outwardly and downwardly toward the sides of the cabinet.

In operation when the burner is lighted the air within the cabinet will be heated and by convection will flow outwardly through the outlet openings in the upper part of the cabinet. At the same time cool air will be drawn inwardly through the inlet openings near the bottom of the cabinet, thence upwardly through the passages 19 in the partition to the upper compartment where it will be rapidly heated by the diffused flame of the burner.

It will readily be seen that I have provided a cabinet arranged to contain a liquid fuel oil burning apparatus which is capable of generating a high degree of heat. Moreover, the construction of the cabinet is such that it may readily and easily be moved from place to place without disturbing the heating element within.

20 I claim as my invention:

An air heater for heating the air in a room comprising, in combination, an upright cabinet, a solid transverse partition intermediate the ends of said cabinet completely dividing 25 said cabinet into an upper and a lower compartment, said cabinet having a plurality of

warm air outlet openings in the upper portion of the upper compartment and a plurality of cold air inlet openings in the lower portion of the lower compartment, a pressure-operated liquid-fuel burner system positioned within the cabinet, said system including a burner mounted on said partition centrally thereof and a liquid fuel supply and pressure tank connected thereto and enclosed within 30 said lower compartment, a baffle-plate mounted in said upper compartment overlying said burner in a plane beneath said air outlet openings and having its edges spaced from the side walls of said upper compartment, and a pair 35 of doors in one wall of the cabinet opening respectively into the upper and lower compartments to give access to said burner and tank equipment, said partition having a series of openings therethrough encircling said 40 burner to effect the flow of air from the lower compartment upwardly around all sides of the burner and baffle-plate and thence through said outlet openings at the top of said cabinet.

45 In testimony whereof, I have hereunto affixed my signature.

OTTO E. HEISSE
